APPARATUS FOR AND METHOD OF
CONDITIONING TEXTILE FIBERS

Edward Hurst, West Newton, Mass., assignor to
B. F. Perkins & Son, Inc., Holyoke, Mass., a corporation of Massachusetts

Application February 15, 1946, Serial No. 647,749

7 Claims. (Cl. 19—65)

1

This invention relates to improvements in apparatus for and methods of conditioning textile fibers.

The principal objects of the invention are directed to novel apparatus for and methods of conditioning textile fibers of all kinds by breaking up foreign substances therein for the removal thereof. While reference will hereinafter be made to animal fibers, such as wool fibers, it will be understood that the same is for purposes of disclosure and that the novel features of the invention are adapted for use with fibers in general and at various stages in the processing thereof such as subsequent to a carding operation, between first and second carding or otherwise all as may be desired.

It is well known that wool fibers contain foreign matter or bodies which must be removed or separated from the fibers for the desired subsequent processing of the fibers.

Such foreign substances take many forms such as vegetable particles consisting of burrs, seeds, leaves, stalks, small twigs, and pieces of wood, manure, dirt and the like which are usually elongated bodies. The bodies are considerably larger in size than the fibers which are ordinarily in the neighborhood of one thousandth of an inch in diameter. These foreign bodies have an inherent tendency to cling to the scales or serrations of the fibers, are usually disposed in opposition to the fibers and are entangled therewith to large extent.

It has been known to pass a thin web of fiber through the bite of smooth coacting pressure rolls in an attempt to remove foreign substances or to facilitate the removal thereof but the results, however, have not been satisfactory for many reasons. More particularly the foreign particles are crushed and flattened out by these rolls so as to tend to adhere more securely to the fibers and make removal difficult if not impossible while the fibers themselves are broken and otherwise injured by the pressure employed.

According to the novel features of the inventions hereof, the foreign bodies are subjected to comminuting and pulverizing action, so that the particles are readily and easily released by the fibers. This is accomplished in a broad way by passing the fibers in the form of a sliver through successive pairs of coacting drawing rolls and then through successive pairs of extender rolls.

By passing the sliver through the drawing rolls it is progressively flattened and attenuated or drawn out to form a relatively thin web. By

5 the drawing action the fibers are elongated from their natural more or less kinked condition and brought into parallelism which action tends to bring the particles or bodies of foreign matter which are usually elongated into parallelism with the fibers. That is the foreign substances which are ordinarily elongated bodies are displaced from their haphazard positions into substantial parallelism relative to the fibers for the action of the first extender rolls.

10 These extender rolls in a general way are provided with surfaces formed with axially or longitudinally extending coacting alternate teeth and grooves arranged and adapted for a rolling and sliding action. As the web passes therebetween the teeth act on the foreign bodies in such a way as to divide them into shorter lengths by a tensioning and sliding action. The said teeth are arranged and adapted to act on the foreign bodies with this sliding and rolling action so that 15 said bodies are not only divided but there may be some pulverizing action as well, all without injury to the fibers. This is to be distinguished from the action of coacting smooth surfaced pressure rolls which press on the foreign bodies to crush and flatten them as well as press on the fibers to injure them.

20 From the last pair of drawing rolls to the first extender rolls there may be a drawing action for further bringing the foreign bodies into parallelism with the fibers and finally and subsequent to the first extender the divided portions of the foreign bodies are divided transversely or split longitudinally by the second extender rolls as the 25 web passes therethrough. These rolls have surfaces formed with longitudinally spaced circumferentially extending alternate coacting teeth and grooves. The thin web of fibers including the shorter foreign bodies passes between these extender rolls the teeth of which are adapted to 30 act on the foreign bodies with a sliding or splitting action for a lengthwise separation thereof without injury to the fibers. There may be provisions for a drawing action between the first and second extender rolls if desired.

35 By subjecting the fibers to the drawing action so as to align the foreign bodies with the fibers and then subjecting the bodies to the first and second extenders the said bodies are first separated longitudinally into relatively shorter lengths which are thereafter split lengthwise. The operations referred to in a general way result in a very great reduction in the size of the foreign bodies so that they are easily and readily 40 released by the fibers by any suitable vibrating 45

50 55

or other means thereby providing fiber which is uniform in all important characteristics and adapted for oiling and other subsequent operations.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Figs. 1 and 2 are plan and side elevational views respectively of conditioning apparatus embodying the novel features of the invention;

Fig. 3 is a partial transverse sectional elevational view at an enlarged scale through adjacent portions of the first extender rolls; and

Fig. 4 is a partial longitudinal sectional view at an enlarged scale through adjacent portions of the second extender rolls.

Referring now to the drawings more in detail, the invention will be fully described.

A base is provided which may be formed from side members 2 which are secured together in spaced relation by transverse members 4. Brackets 6 are disposed in transversely spaced relation at opposite sides of the base at one end thereof to which they are secured in any suitable manner. Said brackets 6 are provided with openings 7 for the shafts of the draft rolls as shown.

Bearings 8 are secured to opposite sides of the base at the opposite end thereof by any suitable means and spaced rods 10 having their lower ends secured to the base extend upwardly therefrom.

Rods 12 which are arranged in pairs have their lower ends secured to flanges 9 of the brackets 6 and extend upwardly with their upper ends secured in flanges 14 of the said brackets. Lower bearings 16 on said rods 12 rest on flanges 9 of the brackets 6 and upper bearings 18 are movable up and down on said rods.

Upper and lower draft or drawing rolls such as 20 forming first, intermediate and third pairs thereof have shafts 21 and 23 respectively at opposite ends thereof which are journaled in the bearings 16 and 18 respectively.

Springs 24 on the rods 12 above the upper bearings 18 urge the bearings downwardly so as to exert yielding pressure to the rolls 20 of the pairs thereof. Stops 26 which may be in the form of cap screws or the like in threaded engagement with the flanges 14 of the brackets 6 are adapted for up and down adjustment and to be engaged by the upper bearings 18 so as to limit upward movements thereof.

Bars 30 are movable on each pair of rods 12 and have bearings 32 and 34 fixed to the undersides thereof in any suitable manner.

Upper and lower first extender rolls such as 36 have shafts 37 and 39 at opposite ends thereof which are journaled in the bearing 32 and the bearings 8 therebelow. These rolls constitute what may be called a first extender.

Upper and lower rolls such as 40 have shafts 41 and 43 at opposite ends thereof which are journaled in the bearings 34 and the bearings 8 therebelow. These rolls constitute what may be called a second extender.

Springs 44 on the upper ends of rods 10 disposed between thrust washers 46 and the ends of the bar 30 with nuts 48 in threaded engage-

ment with the rods provide means for exerting yielding pressure whereby the extender rolls of the pairs thereof may coact with the desired yielding pressure. However any other pressure means desired may be employed.

The drawing rolls of each pair thereof are operatively connected for simultaneous rotation by interengaging gears 50 which are secured to the shafts 21 and 23 thereof while the rolls of the 10 extender are similarly connected by gears 52 and 54.

Any one of the shafts described may be the driving shaft of the apparatus but for purposes of disclosure it will be assumed that the shaft 43 is the main drive shaft. Said shaft 43 may be operatively connected to any suitable source of power.

Intermeshing gears 60 and 62 are fixed on shafts 43 and 37 whereby the upper one of the 20 extender rolls 36 is driven. Gears 64 and 66 are fixed on the shaft 37 and on the shaft 23 of the lower draft roll 20 of the third pair thereof whereby said shaft 23 is driven. Gears 68 and 70 are fixed to this shaft 23 and to shaft 21 of the 25 upper roll 20 of the intermediate pair thereof. Gears 72 and 74 are fixed to said shaft 21 and to shaft 23 of the lower roll 20 of the first pair thereof.

The gearing may be varied within wide limits 30 the foregoing being intended to operate the rolls of the pairs thereof simultaneously while the draft rolls of the intermediate pair are driven at greater peripheral speed than those of the first pair, those of the third pair at a greater peripheral speed than those of the intermediate pair and those of the first extender at a greater speed than those of the third pair of draft rolls.

With the rolls in rotation a sliver of fibers is 40 passed into and through rolls 20 of the first pair thereof and through the successive pairs of rolls. The action between the pairs of draft rolls and between the third pair thereof and the first extender is such as to draw and form the sliver into a thin web. The drawing action is intended to 45 straighten out or elongate the fibers from their somewhat kinky condition and bring the foreign bodies into parallelism with the fibers. That is the drawing displaces or orients the foreign bodies from their haphazard relationship into a more 50 definite parallelism relative to the fibers preparatory to the action of the extenders.

The drawing or draft between the pairs of rolls 55 may be varied from the first pair of draft rolls to the first extender and the draft between adjacent pairs of rolls may be similar or different all as may be desired. As an example, the draft from the first drawing to the first extender may be approximately ten to one with the draft between adjacent pairs of rolls approximately three to one.

According to the invention, it is desired that 60 the foreign bodies carried by the web be disposed in parallelism with the fibers when entering the rolls of the first extender and this may be accomplished by providing such a draft as will 65 straighten out and elongate the fibers sufficiently to orient the foreign bodies into the desired parallelism.

Longitudinal teeth 80 of the extender rolls 36 are shown at an enlarged scale in Fig. 3 and will 70 preferably be approximately of the formation shown. As the fibers and the foreign bodies pass into and through or between the teeth 80 which coact with a rolling and sliding action the bodies are subjected to tension more particularly by being engaged between adjacent sides of adjacent

teeth, so as to stretch or elongate them which results in breaking the objects into relatively shorter lengths as indicated by 82. The fibers being smaller than the foreign bodies and because of their inherent ability to elongate or stretch they pass through the rolls 36 without being acted upon by the teeth of the rolls, while the foreign bodies are divided into very short lengths thereby to facilitate the ready and easy removal thereof from the fibers. The teeth 80 are relatively small as for instance of a circular pitch of about one-sixteenth of an inch it being desired that the foreign bodies be divided into lengths measuring but small fractions of an inch, say $1/64$ " or thereabouts.

Longitudinally spaced teeth 90 of the extender rolls 40 are shown at an enlarged scale in Fig. 4 and will preferably be approximately of the formation shown. As the fibers and the foreign bodies pass into and through or between the teeth 90 they are engaged more particularly between adjacent sides of adjacent teeth which coact in a sliding and rolling manner so as to divide or separate the particles of the bodies lengthwise. To divide the particles of the bodies into small pieces which is desirable for the ready and easy removal thereof from the fiber the teeth 90 are relatively small and may be of a longitudinal pitch equal to about one-sixteenth of an inch or thereabouts.

The nuts 48 may be adjusted to obtain the desired pressure of the extender rolls for the most efficient operation thereof.

Thus by first orienting the foreign objects into parallelism with the fibers, dividing them into shorter lengths and then in dividing them lengthwise in combination with what pulverizing action the extender rolls are capable of the foreign objects are reduced greatly so as to be readily and easily releasable from the fibers. Relatively small particles of the foreign bodies produced by the action of the extenders may be released in the apparatus but such particles as are carried by the web will be very readily removed, subsequent to the final extender action, by any suitable means.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Apparatus for conditioning elongated wool fibers by the removal of foreign bodies dispersed therein comprising in combination, successive pairs of rotatable draft rolls for receiving an elongated sliver of elongated fibers having separate foreign bodies dispersed therein and drawing the same in a certain direction into a web to position the fibers in substantial parallelism and the said bodies in parallelism therewith, a first pair of coacting extender rolls for receiving and moving said web in said certain direction and dividing said foreign bodies into shorter lengths and transversely to said fibers and certain direction, a second pair of coacting extender rolls for receiving and moving said web in said certain direction and splitting said shorter lengths

of foreign bodies in substantial parallelism with fibers and said certain direction, and operative connections between said pairs of rolls and the rolls of said pairs to rotate them in timed relation.

2. Apparatus for conditioning elongated wool fibers by the removal of foreign bodies dispersed therein comprising in combination, successive pairs of rotatable draft rolls for receiving an elongated sliver of elongated fibers having separate foreign bodies dispersed therein and drawing the same in a certain direction into a web to position the fibers in substantial parallelism and the said bodies in parallelism therewith, a first pair of coacting extender rolls for receiving and moving said web in said certain direction and dividing said foreign bodies into shorter lengths and transversely to said fibers and certain direction, a second pair of coacting extender rolls for receiving and moving said web in said certain direction and splitting said shorter lengths of foreign bodies in substantial parallelism with fibers and said certain direction, and operative connections between said pairs of rolls and the rolls of said pairs to rotate them in timed relation, said pairs of draft rolls being spaced apart and said pairs of extender rolls being spaced apart and from said draft rolls.

3. Apparatus for conditioning elongated wool fibers by the removal of foreign bodies dispersed therein comprising in combination, successive pairs of rotatable draft rolls for receiving an elongated sliver of elongated fibers having separate foreign bodies dispersed therein and drawing the same in a certain direction into a web to position the fibers in substantial parallelism and the said bodies in parallelism therewith, a first pair of coacting extender rolls for receiving and moving said web in said certain direction and dividing said foreign bodies into shorter lengths and transversely to said fibers and certain direction, a second pair of coacting extender rolls for receiving and moving said web in said certain direction and splitting said shorter lengths of foreign bodies in substantial parallelism with fibers and said certain direction, and operative connections between said pairs of rolls and the rolls of said pairs to rotate them in timed relation, said pairs of draft rolls being spaced apart and said pairs of extender rolls being spaced apart and from said draft rolls, said first extender rolls having peripheral surfaces formed by circumferentially spaced longitudinally extending alternate teeth and grooves and said second extender rolls having surfaces formed by longitudinally spaced circumferentially extending alternate teeth and grooves, the grooves and teeth of coacting rolls adapted to engage therebetween the foreign bodies and the divisions thereof and act thereon with a sliding action.

4. Apparatus for conditioning elongated wool fibers by the removal of foreign bodies dispersed therein comprising in combination, successive pairs of rotatable draft rolls for receiving an elongated sliver of elongated fibers having separate foreign bodies dispersed therein and drawing the same in a certain direction into a web to position the fibers in substantial parallelism and the said bodies in parallelism therewith, a first pair of coacting extender rolls for receiving and moving said web in said certain direction and dividing said foreign bodies into shorter lengths and transversely to said fibers and certain direction, a second pair of coacting extender rolls for receiving and moving said web in said certain direction and splitting said shorter lengths

rection and splitting said shorter lengths of foreign bodies in substantial parallelism with fibers and said certain direction, and operative connections between said pairs of rolls and the rolls of said pairs to rotate them in timed relation, said pairs of draft rolls being spaced apart and said pairs of extender rolls being spaced apart and from said draft rolls, said first extender rolls having peripheral surfaces formed by circumferentially spaced longitudinally extending alternate teeth and grooves and said second extender rolls having surfaces formed by longitudinally spaced circumferentially extending alternate teeth and grooves, the grooves and teeth of coacting rolls adapted to engage therebetween the foreign bodies and the divisions thereof and act thereon with a sliding action, and means to impart yielding pressure to the extender rolls of the pairs thereof.

5. A continuous method of conditioning elongated wool fibers to facilitate the removal therefrom of separate foreign bodies therein which consists in, drawing fibers in the form of a sliver into the form of a web to position the fibers in substantial parallelism and positioning the bodies in parallelism therewith, subjecting the web to the action of means to divide the bodies into shorter lengths and transversely to said fibers and finally in subjecting said web to the action of means to split the shorter lengths of bodies in substantial parallelism with the fibers.

6. A continuous method of conditioning elongated wool fibers to facilitate the removal therefrom of separate foreign bodies therein which consists in, drawing fibers in the form of a sliver into the form of a web and positioning the fibers

in substantial parallelism and positioning the bodies in parallelism therewith, subjecting the web to the action of means to further draw said web and to divide the bodies into shorter lengths and transversely to said fibers and finally in subjecting said web to the action of means to split the shorter lengths of bodies in substantial parallelism with the fibers.

7. A continuous method of conditioning elongated wool fibers to facilitate the removal therefrom of separate foreign bodies therein which consists in, drawing fibers in the form of a sliver into the form of a web and positioning the fibers in substantial parallelism and positioning the bodies in parallelism therewith, subjecting the web to the action of means to further draw said web and divide the bodies into shorter lengths and transversely to said fibers and finally in subjecting said web to the action of means to further draw said web and split the shorter lengths of bodies in substantial parallelism with the fibers.
